UNITED STATES PATENT OFFICE.

EDWARD CLAXTON WALTER, OF ORANGE, NEW JERSEY, ASSIGNOR TO THE ELLIOTT-FISHER COMPANY, OF NEW YORK, N. Y., A CORPORATION OF DELAWARE.

SELECTIVE GEAR TRANSMISSION FOR CALCULATING MACHINES.

Application filed April 21, 1925. Serial No. 24,770.

This invention relates to a selective mechanism for calculating machines, of the type in which the indicating wheels are rotated by selecting mechanism which is set by keys and is operated by a crank or other motor.

The object of the invention is to provide a machine of this character with efficient selecting mechanism occupying a minimum of lateral space to permit a minimum spacing of the indicating wheels and operated or set by a series of number keys, each of which operates or sets a single selecting member to secure the full value of the key in the computation.

15 To the accomplishment of the stated objects and others subordinate thereto, a preferred embodiment of the invention is illustrated in the accompanying drawings, in which:

Figure 1 is an elevation of an index wheel, 20 its setting and operating mechanism and a series of number keys, the connection between which and the setting mechanism is more or less diagrammatic.

Figure 2 is a view at right angles to Figure 25 1, and

Figure 3 is a diagrammatic view of the intermediate gear and the selectors.

1 indicates an indicating wheel mounted on a shaft 2 and associated with a gear 3, spaced 30 to secure a movement of the index wheel 1, which will advance the digits 4 on the periphery of the index wheel before a sight opening in the casing of the machine in the usual way.

Parallel with the shaft 2 are a pair of selector shafts 5 and 6, which may be, and preferably are, driven from a common source of power, as, for instance, a crank 7 on an operating shaft 8, having a gear 9 meshed with gears 10 and 11 on the shafts 5 and 6. The 40 arrangement is such that the shafts 5 and 6 always rotate in the same direction relative to each other, but may be rotated in opposite directions for addition and subtraction by rotating the handle 7 in one direction or the 45 other.

Splined on the shafts 5 and 6 are selectors 12 and 13, rotatable with the shafts but slideable thereon to different set positions. The selectors 12 and 13 are cylindrical in 50 form and each has peripheral flanges or teeth 14. The teeth of the selector 13 are 4 in number and of graduated lengths, terminating at different distances from the end of the selector nearest the gear 3.

By shifting the selector 13 a single increment to the left in Figure 1, a single tooth 14 will come into the plane of operation. That is to say, in this position of the selector its rotation will cause a single tooth to engage the gear 3 and operate the same a single increment of movement to advance the index wheel from one digit to the next, as, for instance, from 1 to 2 in addition, or 2 to 1 in subtraction.

A further increment of movement of the selector would present two teeth in operative position and the third and fourth positions will present 3 and 4 teeth in position to operate the gear 3 in an obvious manner. These varying degrees of selecting movement of the member 13 are effected by the depression of the first 4 keys 15 of a row or bank of 9 as indicated in the drawing.

Mechanisms whereby this character of setting movement is imparted to a selecting member by the keys of a calculating machine are well-known in the art. Therefore, as my invention resides in the mounting and movement of the selectors and not in the specific means for moving them, I have indicated the moving mechanism more or less diagrammatically by showing two setting levers 16 and 17, which, when swung, will move the selectors toward and from the gear 3, connected in any suitable manner with appropriate number keys 15 to secure the desired degree of setting movement by the operation of a selected key. The selecting mechanism herein claimed is designed for use in a well known type of calculating machine in which selectors are moved both singly and in unison the necessary distance in the required direction by shifting elements or yokes moved by cams connected to keys of a row or bank. Such a machine is disclosed in Reissue Patent #13,841 to Baldwin. The use of the Baldwin key operated selector shifting mechanism is contemplated with such variations of the cam surfaces as will obviously be necessary to secure the described movement of the selectors.

Teeth 14 of the setting member 12, are nine in number, as shown in Figure 3. Five of these teeth terminate in the same plane and are presented in operative position by a single increment or step of movement of the selecting member. The last five teeth are graduated in length so that each step of movement of the selector beyond the position in which

five teeth are effective will bring an additional tooth into operative position until all nine are located in the plane of the gear 3.

In performing calculations, the addition or subtraction of values 1 to 4 is secured by setting the selecting member 13 in any one of four positions by the depression of the appropriate one of the first four keys. Similarly the addition or subtraction of the values 5 to 10 9 is secured by setting the member 12 by the depression of the appropriate one of the last five keys, that is keys 5 to 9.

Attention is now directed to the fact that while the range of selection is from 1 to 9, it is secured by a maximum of five increments of setting movement of the selecting mechanism. Also, it will be noted that by mounting the setting members on separate shafts, said members move in different planes and their movement may therefore overlap in a manner to permit a very compact arrangement of the parts in comparatively close spacing of the index wheels. Also, it will be noted, as heretofore stated, that these results are secured in a manner to permit any desired selection without the necessity for having any one key impart a setting movement to more than a single selecting element. In other words, there is not, at any time, conjoint action of the selectors to select values 1 to 9. As a result the load on the keys is lighter and more uniform as regards each key, and when compared with that imposed by concurrent setting of two selectors for certain values, as in the above noted type of machine. It follows that the load on the crank, or motor, is also appreciably lessened as will be clear without further explanation. It will, of course, be understood that in a machine of this character the group of elements which has been described is duplicated for each denominational position up to the capacity of the machine.

It is thought that from the foregoing the construction and operation of my selecting mechanism will be clearly understood, but I reserve the right to effect such modifications thereof as may come fairly within the spirit of the invention.

What I claim is:—

50 1. A selecting mechanism for calculating machines, including a plurality of selecting members for a single denominational position and having parallel axes.

55 2. The combination with an index wheel, a plurality of selecting members rotatable to operate the index wheel, and disposed out of axial alignment.

60 3. The combination with an index wheel, of plurality of selecting members rotatable to operate the wheel independently of each other to indicate all values from 1 to 9.

4. The combination with an index wheel, of

two selecting members rotatable on parallel axes to operate the index wheel, one of said selecting members being settable in positions 65 to operate the index wheel for a progressive number of digital values and the other member being settable in different positions to operate said wheel for consecutive values beyond those first named.

5. The combination with an index wheel, of two selecting members, a series of keys representing the values 1 to 9, and means whereby 70 one of the selecting members will be settable in four set positions, and whereby the other selecting member may be settable in five set positions.

6. In a selecting mechanism for calculating machines, the combination with parallel 75 shafts, of selecting members mounted on said shafts to select values in the same denominational position.

7. The combination with a series of keys and a denominational member of intermediate 80 selecting mechanism, including a plurality of setting members rotatable about different axes to operate the denominational member, and means for rotating the selecting members.

8. The combination with a gear of parallel 85 shafts and selecting members mounted on the shafts, and settable in different positions to operate the gear for different values.

9. The combination with an index wheel, of a gear associated therewith, parallel selector 90 shafts, means for driving said shafts, selecting members rotatable with the shafts, and shiftable thereon to different set positions in which the index wheel will be operated for different values, and keys for setting the selecting members.

10. The combination with an index wheel and a gear associated therewith, of parallel selector shafts, cylindrical selecting members rotatable with the shafts, and shiftable thereon in opposite directions to different set positions relative to the gear, graduated teeth on the selecting members, means for driving the shafts, and keys for setting the selecting members.

11. The combination with an index wheel, of a selecting mechanism, including selecting members arranged to operate the index wheel, one for the values 1 to 4, and the other for the values 5 to 9.

12. The combination with a denominational 115 member operative to accumulate values 1 to 9, of a pair of selectors for differentially controlling operation of said member, said selectors being independently settable to effect between them accumulation of values 1 to 9 120 by said member.

In testimony whereof, I affix my signature.

EDWARD CLAXTON WALTER.
